[57] CLAIM

The ornamental design for a sling and seat restraint for children, as shown and described.

DESCRIPTION

FIG. 1 is a front elevational view of the sling and seat restraint for children of the present invention, rear elevational view being a mirror image thereof;

FIG. 3 is a left side elevational view of the sling and seat restraint for children of FIG. 1, the right side elevational view being a mirror image thereof;

FIG. 4 is a top plan view of the sling and seat restraint for children of FIG. 1; and,

FIG. 5 is a bottom plan view of the sling and seat restraint for children of FIG. 1.

The broken lines showing of a child and a highchair in FIG. 2 are for illustrative purposes only and form no part of the claimed design.

The fragmentary criss-cross pattern shown on the sling and seat restraint for a children is understood to represent fabric and is repeated uniformly throughout the areas shown.
